(57) **CLAIM**

The ornamental design for a toiletry bag, as shown and described.

DESCRIPTION

FIG. 1 is a right side, top, front perspective view of a toiletry bag showing our new design;

FIG. 2 is a right side elevation view of the toiletry bag of FIG. 1;

FIG. 3 is a left side elevation view of the toiletry bag of FIG. 1;

FIG. 4 is a rear elevation view of the toiletry bag of FIG. 1;

FIG. 5 is a front elevation view of the toiletry bag of FIG. 1;

FIG. 6 is a top plan view of the toiletry bag of FIG. 1; and,
FIG. 7 is a bottom plan view of the toiletry bag of FIG. 1.
The dashed lines represent stitching on the toiletry bag that
form a part of the claimed design.

1 Claim, 7 Drawing Sheets
